SHAPED CHARGES

Joseph H. Church, Austin, Minn., and Gregory J. Kessenich, Madison, Wis., assignors to the United States of America as represented by the Secretary of the Army

Application May 12, 1950, Serial No. 161,672

3 Claims. (Cl. 102—24)

(Granted under Title 35, U. S. Code (1952), sec. 266)

The invention described herein may be manufactured and used by or for the Government of the United States of America for governmental purposes without the payment to us of any royalty thereon or therefor.

This invention relates to "shaped" charges especially adapted to use for special purposes, such as the production of a series of closely spaced holes in a target.

The charge of this invention is especially adapted for use with the apparatus shown in copending application Serial Number 159,914, filed May 4, 1950, which matured to U. S. Patent No. 2,682,834 on July 6, 1954.

Various objects of the invention will be apparent from the following description when considered with the appended drawings, in which:

Fig. 1 is a plan view of a preferred form of charge embodying the features of this invention.

Fig. 2 is a sectional view taken upon the line 2—2 of Fig. 1.

Fig. 3 is a sectional view similar to Fig. 2 showing a modified form of charge.

Fig. 4 is a sectional view similar to Figs. 2 and 3 showing another modified form of charge.

Fig. 5 is a longitudinal sectional view of a fuse especially adapted to use for detonating charges of the type shown herein, and

Fig. 6 is a sectional view taken upon the line 6—6 of Fig. 5.

The charge 10 as shown in Figs. 1 and 2 comprises an explosive body 11 formed of any appropriate detonable explosive which is symmetrically arranged about a central axis 12 and bounded by opposed parallel surfaces 13, 14. The latter opposed surfaces are joined by an intervening edge surface 15 to define a peripheral bounding edge surface for the explosive body. At uniformly spaced intervals circumferentially of the body the edge surface 15 is indented to provide a plurality of radial symmetric reentrant primary cavities 16, which as shown, open radially outward of the charge in diverging relation. Although the cavities 16 are shown to be of modified or general V-shape in horizontal cross-section it is to be appreciated that they may be of any suitable radial symmetric cross section.

The peripheral edge surface 15 may throughout each indented portion thereof be further recessed in symmetric relation to a median plane 17 of the explosive body 11 to form a secondary cavity 18 within each of the primary cavities 16. As in the case of the primary cavities the secondary cavities 18 may likewise be of any appropriate symmetric form.

The explosive body 11 is formed with an axial bore 19 suitable to receive an ordinary primacord or similar fuse, or the fuse shown in Fig. 5 and hereinafter described.

To encase the charge, opposed plates 20, 21 conforming in plan form to the charge are joined in any suitable manner by a peripheral plate 22 comprised of sections 23 which are complementary to the primary and secondary cavities 16, 18, and which in addition serve as liners for the cavities. The plates 20, 21 and 22 may be formed

2

of any metallic or non-metallic material suitable for the purpose.

The charge shown in Fig. 3 is similar in all respects to the charge shown in Figs. 1 and 2 except that the opposed parallel surfaces 24, 25 are conical in form whereby the directed force effect accomplished by each of the cavities will be at an angle other than normal to the axis 12 of the charge which is advantageous in the charge when used in some environments.

10 In Fig. 4 we have shown a modified form of charge which is similar to the charge shown in Figs. 1 and 2. In this case the primary cavities 26 are of different symmetric form than the primary cavities shown in Figs. 1 and 2 and the explosive body has been cavitated so as to permit portions 27 thereof to extend to the periphery of the charge over and under the cavities as shown. The opposed charge encasing plates in this case are shown as circular plates 28, 29 which extend to the periphery of the charge and may carry inwardly projecting flanges 30 which in turn support strips 31 of any suitable material to retain the liners 32 and explosive portions 27 in place.

We may also use circular plates in lieu of the plates 20 and 21 in any case where it is desirable to cover opposed sides of the cavities 16 in the planes of the plates 20, 21.

25 The charges we have shown may be detonated by primacord extending through the bores 19 formed in the charges. In this system, using a primacord detonator, detonation of the explosive body 11 will be progressively propagated along bore 19 from a point adjacent either surface 13 or 14 through the entire charge. If the detonation velocity of the primacord is greater than that of the explosive body, the rate of initiation along bore 19 will be equal to the detonation velocity of the primacord, and the desirable instantaneous initiation of the walls of bore 19 can be approached. This system because of its simplicity and comparative good results can ordinarily be tolerated, however, where greater efficiency of the charge is desired we prefer to use a detonator or initiator of the 30 type shown in Figs. 5 and 6.

35 As indicated the detonator 33 may be comprised of a tubular element 34 made of any appropriate metallic or non-metallic material intended to function primarily as a housing element for the detonator. Within the element 34 there is inserted a tubular element 35 of detonable explosive exteriorly shaped to provide a plurality of radial symmetric outward opening cavities 36 uniformly spaced circumferentially of the element and extending in linear parallel axial relation thereof. A resistance element 37 is disposed through the bore of the tubular explosive element 35 in central relation thereto and is connected integrally or otherwise suitably affixed at either end to leads 38, 39 adapted to be circuited with a source of power not shown. Fuse powder 40 adapted to be ignited by resistance element 37 and in turn adapted to detonate the tubular explosive element 35 is packed within element 35 about the resistance element in any convenient manner. The ends of the tubular casing element 34 may be plugged with plugs 41 of sulphur or similar material to prevent moisture from gaining access to the interior of the detonator assembly. Depending upon the character of the explosive used to form the body 11 a booster may or may not be employed in conjunction with the detonator as will be well understood in the art.

40 We claim:

45 1. A shaped explosive charge comprising a pair of identical star-shaped sheets of material having uniformly angularly spaced arms, means connecting said sheets in parallel axially spaced relation, said means comprising a strip of material having parallel edges secured to and 50 extending along the respective contiguous edges of said star-shaped sheets to form therewith a completely closed

star-shaped container, said strip of material having an inwardly projecting continuous channel generally V-shaped in radial cross section and between and parallel with its edges, and an explosive charge completely filling said closed container.

2. A shaped explosive charge comprising a pair of identical star-shaped sheets of material having uniformly angularly spaced arms, means connecting said sheets in parallel axially-spaced relation, said means comprising a strip of material having parallel edges secured to and extending along the respective contiguous edges of said star-shaped sheets to form therewith a completely closed star-shaped container, said strip of material having an inwardly projecting continuous channel generally V-shaped in radial cross section and between and parallel with its edges, and an explosive charge completely filling said closed container, the arms of said star-shaped sheets being truncated to lie in the surface of a common cylinder coaxial with the central axis of said sheets.

3. A shaped explosive charge comprising a pair of identical star-shaped sheets of material having uniformly angularly spaced arms, means connecting said sheets in parallel axially spaced relation, said means comprising a strip of material having parallel edges secured to and

extending along the respective contiguous edges of said star-shaped sheets to form therewith a completely closed star-shaped container, said strip of material having an inwardly projecting continuous channel generally V-shaped in radial cross section and between and parallel with its edges, and an explosive charge completely filling said closed container, said sheets being in the form of right cones of equal obtuse apex angles with coincident axes.
